UNITED STATES PATENT OFFICE

2,586,001

HANGER

Arley D. Carpenter, Los Angeles, and Charles A. Slater, Bellflower, Calif., assignors, by direct and mesne assignments, to The Norco Co., Los Angeles, Calif., a copartnership

Application July 11, 1945, Serial No. 604,406

3 Claims. (Cl. 248—68)

1

The present invention relates to hangers of the type which may be utilized for securing in position various instrumentalities such as marine cables, pipes, conductors and the like, at any location desired whether it be in a ship, building, rolling stock or elsewhere.

An object of the invention is the provision of a hanger which is easily, quickly, conveniently and satisfactorily assembled for support and disposition of cables, pipes, conductors and the like, of the same or different diameter, in suitable arrangement in ships, buildings, rolling stock and other places.

A further object of the invention is the provision of a hanger which will securely hold cables and the like without becoming loosened due to excessive vibration in the structure to which the hanger is attached.

The present invention has been subjected to vibration tests at the rate of 4000 strokes per minute, and has been found to remain tight after 60 minutes continuous vibration. Despite the fact that the present hanger secures the work firmly in place without loosening due to vibration, still the hanger is rapidly assembled or disassembled as the necessity arises.

The invention has for a further object a hanger which is inexpensive in cost to manufacture and is generally superior to devices now known to the inventor.

With the above mentioned and other objects in view, the invention consists in the novel and useful provision, formation, construction, association and relative arrangement of parts, members and features, all as shown in a certain embodiment in the accompanying drawing, described generally and more particularly pointed out in the claims.

In the drawing:

Fig. 1 is a front elevation of the improved hanger shown in cooperation with the work;

Fig. 2 is a plan view of a hanger bar used in the invention;

Fig. 3 is a perspective view of a clamp used in the practice of the invention;

Fig. 4 is a fragmentary, partially sectioned view of the invention taken on line 4—4 of Fig. 1, shown in cooperation with work;

Fig. 5 is a perspective view of a locking spring member used in the invention;

Fig. 6 is a side elevation, partly in section, of the locking spring shown in Fig. 5, together with an adjusting screw therefor;

Fig. 7 is a bottom plan view of the locking spring shown in Fig. 5; and

2

Fig. 8 is a modified form of screw adjustment for the locking spring.

Referring now to the drawing:

We provide a hanger bar 1, formed and constructed to suitably accommodate a U-shaped strap clamp 2, of which there may be a plurality and of different sizes, which clamp is held to said hanger bar by a spring locking keeper 3. The hanger bar may take any form desired, but preferably should be of channel cross-section as best illustrated in Fig. 2. The hanger bar includes a base portion 4 and two leg portions 5 and 6. The bar includes a portion 7 upon which the work is disposed, with two angularly bent ends 8 and 9 adapted to be secured in any convenient manner to depending supports 10 and 11 attached beneath the flooring or other structure 12. In the present instance we secure the ends 8 and 9 to the members 10 and 11 respectively by means of bolts designated generally as 13. The base 4, and specifically the portion 7, is provided with one or more elongated slots 14. These slots are of such width as to accommodate the strap clamps 2 and provide ledge portions 15 and 16 on opposite sides of the said slots adjacent to the legs 5 and 6.

The clamp 2 may be of any form desired and of a size to best accommodate the work. In the present instance, the clamp includes two legs 17 and 18 interconnected by a curved portion 19. The legs adjacent the ends are provided with transverse openings 20. In the present instance the said openings are shown as of rectangular section.

The spring locking keeper 3 includes two leaves 21 and 22 interconnected by member 23. The construction is such that the said locking spring is resilient in character and the said leaves tend to separate. Leaf 21 is provided along its marginal edges with angularly related wings or lugs 24 and 25. We preferably so arrange the said wings that they subtend an angle of 45° relative to the plane of the leaf 21, and said wings are likewise positioned intermediate the ends of said leaves. The leaf 21 is provided in its outer end with a threaded bore 26 to accommodate a screw 27 which is flat-ended as shown in Fig. 6 for engaging the under side of the leaf 22.

In the modification shown in Fig. 8 the leaf 22 of the spring locking keeper 3 is provided in its under side with an indentation 28 in alignment with the threaded bore 26, and a screw 29 with a pointed end 30 is threaded through said threaded bore 26 with said pointed end of said

screw received by said indentation 28 for centering said end of said screw.

The operation, uses and advantages of the invention are as follows:

Reference is made to Fig. 4, wherein a cable 31 is transversely passed over the hanger bar 1 and held to said hanger bar by means of the clamp of Fig. 3 and the spring locking keeper of Fig. 5. When the proper sized clamp has been selected, depending upon the diameter of the work, the clamp transversely straddles the cable, with the ends of said clamp passed through one of the longitudinal slots 14 of the hanger bar and in such position that the openings 20 lie beneath the base 4 and in the zone of the legs 5 and 6. The spring locking keeper 3 is of such length as to be transversely accommodated between the legs 5 and 6 of the hanger bar. The leaves of the spring locking keeper 3 are compressed together, and the lugs 24 and 25 are passed through the openings 20 of the clamp. The screw 27 may already be in position between the leaves, but moved outwardly so as not to interfere with compression of the leaves, whereupon the screw is turned to forcibly separate the leaves at their outermost ends, as for instance illustrated in Figs. 5 and 6. Obviously, the outermost leaf 22 will engage the base 4, resting on the ledges 15 and 16 and spanning the slot 14. As the screw 27 is turned, the lowermost leaf 21 is moved downwardly to bring the lugs 24 and 25 into tight engagement with that portion of the clamp 2 bounding the openings 20. The tension of the leaf 21 of the locking spring keeper 3 holds the screw against counter-rotation, and the clamp tightly holds the work against the hanger bar. It is evident that any vibration that occurs in the structure would be communicated to the work through the hanger bar, and by the work and hanger bar to the spring locking keeper. The net result is that vibration does not loosen the screw 27 nor

the locking spring from its engagement with the strap.

In Fig. 1 we have shown an embodiment wherein a series of cables of different sizes are conveniently carried on the hanger bar.

5 We claim:

1. A hanger including a hanger bar upon which work is supported, a U-shaped clamp extended over the work and through said hanger bar, said clamp being provided with openings in its ends, a spring locking keeper comprising a single piece of sheet metal bent upon itself and formed with a pair of spaced spring leaves, one of said leaves engaging said hanger bar and said other spring leaf being formed with a pair of wings extending into said openings in said clamp and engaging said clamp for drawing said clamp upon the work and clamping the work upon said hanger bar.

20 2. A hanger as characterized by claim 1 including means for adjusting the tension of the spring leaves of the spring locking keeper upon the work clamp.

25 3. A hanger as characterized by claim 1 including an adjusting screw threaded in one of the leaves of the spring locking keeper and engaging the other leaf of said keeper for adjusting the tension of said keeper upon the work clamp.

ARLEY D. CARPENTER.
